US00D987746S

(12) **United States Design Patent** (10) **Patent No.:** **US D987,746 S**
Wang (45) **Date of Patent:** **** May 30, 2023**

(54) **PUSH UP DEVICE**

(71) Applicant: **BETO ENGINEERING AND MARKETING CO., LTD.**, Taichung (TW)

(72) Inventor: **Lopin Wang**, Taichung (TW)

(73) Assignee: **BETO ENGINEERING AND MARKETING CO., LTD.**, Taichung (TW)

(**) Term: **15 Years**

(21) Appl. No.: **29/768,290**

(22) Filed: **Jan. 28, 2021**

(30) **Foreign Application Priority Data**

Aug. 5, 2020 (TW) 109304383

(57) **CLAIM**

The ornamental design for a push up device, as shown and described.

DESCRIPTION

FIG. 1 is a perspective view of a push up device showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a perspective view of the design in a state of use. The dashed broken lines depict portions of the push up device in which the design is embodied that form no part of the claimed design.

1 Claim, 6 Drawing Sheets
